UNITED STATES PATENT OFFICE.

WARREN M. FRISBIE, OF YPSILANTI, MICHIGAN.

CIRCULAR-SAW GUARD.

1,244,187.

Specification of Letters Patent. Patented Oct. 23, 1917.

Application filed February 17, 1917. Serial No. 149,249.

To all whom it may concern:

Be it known that I, WARREN M. FRISBIE, a citizen of the United States, residing at Ypsilanti, in the county of Washtenaw and 5 State of Michigan, have invented a new and useful Circular-Saw Guard, of which the following is a specification.

The present invention appertains to saw guards, and aims to provide a novel and 10 improved device of that character for use in connection with circular saws.

It is the object of the invention to provide a circular saw guard embodying a novel 15 assemblage of the component elements, the device being adjustable to suit the conditions, and effectively serving its office of protecting the saw and preventing injury either by objects thrown by the saw, or the accidental falling of a person over the saw.

20 With the foregoing and other objects in view which will appear as the description proceeds, the invention resides in the combination and arrangement of parts and in the details of construction hereinafter described and claimed, it being understood that changes in the precise embodiment of the 25 invention herein disclosed can be made within the scope of what is claimed without departing from the spirit of the invention.

30 The invention is illustrated in the accompanying drawings, wherein:—

Figure 1 is a side elevation of the device as applied.

Fig. 2 is an enlarged section on the line 35 2—2 of Fig. 1.

Fig. 3 is a sectional detail taken on the line 3—3 of Fig. 2.

Fig. 4 is an enlarged vertical section taken on the line 4—4 of Fig. 1.

40 Fig. 5 is a perspective view of the main guard member.

Fig. 6 is a fragmental perspective view of the secondary or auxiliary guard member.

45 In carrying out the invention, there is provided a sheet metal hanger plate 1 having a flange 2 extending at an angle from its upper end and adapted to be secured in any suitable manner to the bottom of the 50 table 3 in rear of the circular saw 4. A slide plate 5 bears against one side of the hanger plate 1, and is provided with lips 6 struck therefrom and working in horizontal slots 7 with which the plate 1 is provided, where- 55 by to guide the slide plate 5 for horizontal adjustments, the slots 7 being longer than

the lips 6. The plate 5 is provided at its side edges with outturned guide flanges 8. A flat bracket 9 is provided at its lower end with a depending flat shank 10 resting 30 against the plate 5 and fitting slidably between the flanges 8. The bracket 9 is of semi-crescent shape, being curved forwardly so as to overhang the saw. The bracket 9 is disposed in the same plane as 35 the saw 4 and projects upwardly above the table 3 to work in the slot or kerf cut in the wood or stock by the saw. The shank 10 of the bracket is provided with a downwardly opening vertical slot 11 for receiving a bolt 12 extending through a central opening or aperture of the plate 5, and a horizontal elongated slot 12' of the plate 1. A nut 13 is threaded upon the bolt 12 to clamp the plates 1 and 5 and shank 10 together, suitable washers being used upon the bolt if desired. By loosening the nut 13, the slide plate 5 can be slid horizontally toward and away from the saw to adjust the bracket 9 likewise, and the bracket can be adjusted 40 vertically. When the nut 13 is tightened, the parts are clamped in the positions to which they have been adjusted, it thus being possible to adjust the bracket 9 both horizontally and vertically in the plane of the saw 4.

Adjustably carried by the bracket 9 is a main guard member 14 of inverted U-shaped cross section, preferably constructed of sheet metal. The back or web portion of the member 14 is adapted to seat on the upper curved edge of the bracket 9 with the flanges or wings of the member 14 depending at the opposite sides of the saw, whereby to provide the desired protection. One flange 90 of the member 14 is provided at one end with an extension 15 adapted to overlap one side of the bracket 9, and the corresponding end of the other flange of the member 14 has a tongue 16 offset toward the extension 95 15, said extension and tongue being provided at their free ends with apertures 16' receiving a bolt 17. The bracket 9 has a series of open slots or notches 18 extending from its upper and rear curved edge for 100 receiving the bolt 17. Thus, when the bolt 17 is loosened, the member 14 can be placed on the bracket 9 and moved longitudinally to move the bolt 17 into the desired slot or notch 18, the member 14 seating on the upper 105 edge of the bracket 9 to hold it in the desired position. The bolt 17 can then be 110

tightened for clamping the member 14 in place, the bracket 9 being clamped between the extension 15 and tongue 16. By placing the bolt 17 in the various slots 18, the angular position of the member 14 can be changed, as will be obvious.

A secondary or auxiliary guard member 19 of inverted U-shaped cross section straddles the guard member 14. One end of the web portion of the member 19 is provided with a hook 20 engageable downwardly through a slot 21 with which the web portion of the member 14 is provided at the free end of said member opposite to the end having the extension 15 and tongue 16. Thus, the hook 20 can be pivotally engaged downwardly through the slot 21, as seen in Fig. 1, with the flanges of the member 19 overlapping and depending from the flanges of the member 14 to ride on the material being cut. The member 19 can be applied and removed readily, and is swingable vertically to coöperate with the member 14 to properly protect the saw.

The various parts are constructed chiefly of sheet metal, being simple and inexpensive to manufacture, and the parts can be readily assembled and applied.

Having thus described the invention, what is claimed as new is:

1. A saw guard embodying an upwardly

projecting bracket having a curved upper edge and a series of guard engaging portions, and a guard member seatable slidably on said upper edge and having means engageable with said portions to hold the guard member in various angular positions.

2. A saw guard embodying an upwardly projecting bracket having a curved upper edge provided with notches, and a guard member seating slidably on said upper edge and having means engageable in said notches for pivotally connecting the guard member with the bracket so that the guard member seats on said upper edge of the bracket.

3. A saw guard embodying main and secondary guard members each of inverted U-shaped section, means for supporting the main guard member, the secondary guard member straddling the main guard member, the main guard member having a slot near one end, and the secondary guard member having a hook engaging through said slot to pivotally connect it with the main guard member.

In testimony that I claim the foregoing as my own, I have hereto affixed my signature in the presence of two witnesses.

WARREN M. FRISBIE.
